(57) **CLAIM**

We claim the ornamental design for a multi-function printer, as shown and described.

DESCRIPTION

FIG. 1 is a top perspective view of a multi-function printer; FIG. 2 is a top plan view thereof;

FIG. 3 is a front elevational view thereof;

FIG. 4 is a right-side elevational view thereof; the left-side elevational view thereof being a mirror image of the right-side elevational view shown; and,

FIG. 5 is a rear elevational view thereof.

The broken lines in the drawings are for illustrative purposes only and form no part of the claimed design.
